FURNACE STOKER

Leonard A. Ward, Denver, Colo.

Application April 16, 1937, Serial No. 137,263

8 Claims. (Cl. 192—150)

This invention relates to a stoker for feeding coal to a furnace and is designed as an improvement over the stoker illustrated and described in applicant's copending application 5 Serial No. 115,714.

The principal object of the invention is to provide a small compact, simple, portable, efficient stoker unit which can be applied to the present household plants without requiring any change 10 in the present heating system.

Other objects of the invention are to provide positive controllable mechanism for feeding the coal to the burner; to provide means for preventing the coal from packing or clogging the stoker; 15 to provide means for breaking lumps of coal to the proper size for feeding to the burner; to provide automatic means for shutting off the operating motor should iron or other non-breakable foreign substances become locked in the mechanism.

Other advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:—

Fig. 1 is a plan view of the improved stoker partially broken away to show the interior construction.

Fig. 2 is a detail section through the burner portion of the device.

Fig. 3 is a left side view of the stoker with the casing partially broken away.

Fig. 4 is a detail sectional view through the feed cam housing.

Fig. 5 is a face view of the feeder cam housing.

Fig. 6 is a vertical cross section through the stoker portion, taken on the line 6—6, Fig. 1.

Fig. 7 is a detail view through the upper extremity of the feed tube.

The invention comprises a cabinet-like housing 10 supported on suitable legs 11 and provided in its lower portion with a supporting frame 12.

50 A coal hopper 13 is formed in the upper portion of the cabinet 10 leading to a laterally extending feed screw chamber 14.

A feed screw 15 is supported in the feed screw chamber 14 upon a feed screw shaft 16. The 55 feed screw chamber 14 opens through a jagged

breaker opening 17 into a feed chamber 18 from which a rotary feed tube 19 leads.

The feed tube 19 is inclined downwardly to a burner base 20 positioned within the ash pit of the furnace. The burner base is formed with a 5 curved passage 21 which directs the coal discharging from the feed tube upwardly into an inverted conical burner 22.

The burner 22 is surrounded by an air chamber 23 and by tuyères 24 formed through the 10 wall of the burner and communicating with the air chamber. Air is supplied to the air chamber 23 through a conduit 25 from a blower 26 within the cabinet 10.

The blower is driven from a suitable electric 15 motor 27, the shaft of which, shown at 28, extends through the blower and terminates in a worm 29 in a gear housing 30 surrounding the feed tube 19. The worm 29 drives a worm gear 31 which is secured on the feed tube 19 and rotates the latter. 20

The gear housing 30 is extended along the feed tube 19 and forms a bearing for the latter. The housing is supported upon suitable brackets 32 from the supporting frame 12. The feed screw 15 is rotated from the rotating feed tube 19 25 through the medium of a tie bar 33 which is welded to the interior of the feed tube at one extremity and rotates a hollow shaft 34 at its other extremity.

The hollow shaft carries a cam 35 within a 30 cam housing 36. A lever 37 rests by gravity on the cam 35. One extremity of the lever is carried on a cross shaft 38. The other extremity of the lever carries a ratchet pawl 39. The ratchet pawl 39 is formed with a counter-weight 40 which 35 constantly holds it in engagement with the teeth of the ratchet wheel 41. The ratchet wheel 41 is fastened on the extremity of the feed screw shaft 16 and rotates the latter. A check pawl 42 is provided to prevent return rotation of the 40 shaft 16. The downward arc of movement of the lever 37 can be limited by means of an adjustment screw 43 positioned beneath the lever.

The cross shaft 38 at the other extremity of the lever 37 passes through vertically slotted holes 44 in the sides of the housing 36 and rests in bottom half bearings 45. The shaft is held down in the half-bearings 45 by upper half-bearings 46 which are carried on the extremities of an inverted U-shaped yoke 47. The yoke 47 is constantly pressed downward by means of a spring 48 which is clamped by a clamp nut 49 on a spring stud 50.

Should a piece of iron, rock or other unbreakable substance reach the feed screw and become 55

lodged in the breaker opening 17 it will become impossible for the ratchet pawl 38 to turn the ratchet wheel 41. The up thrust of the cam 48 will then cause the rearward extremity of the lever 47 to raise. This will push the yoke 47 upward compressing the spring 46 to allow the cam to pass beneath the lever without damage.

Means are also provided for shutting off the motor 27 on such an occasion by placing a press button switch 51 in the path of an arm 52 which is connected with the yoke 47.

The switch 51 is connected in the circuit of the motor 27. Thus, as the yoke moves upwardly in the direction of the broken line in Fig. 5 it will shut off the current supply to the motor 27, stopping the stoker until the obstruction can be removed.

Naturally as the feed tube 18 rotates, the bar 33 will swing in a cylindrical path thus acting as an agitator to prevent clogging of the coal in the feed chamber 18.

Clogging of the coal in the feed tube is prevented by means of an agitator bar 53 which extends throughout the length of the tube adjacent the upper wall thereof and which terminates at its upper extremity in a weighted lever 54.

The weight of the lever 54 prevents the bar 53 from normally rotating with the feed tube unless the coal becomes tightly packed therein, in which case, the lever may rotate. The operator can then manually engage the lever 54 and swing it to break loose any packed coal in the feed tube.

The lower extremity of the bar 53 is journaled on a screw member 55 at the lower extremity of the feed tube. This screw 55 extends outwardly from the lower extremity of the feed tube and is welded or otherwise secured therein so that it will rotate with the tube and force the coal into the burner base 21. The lower extremity of the feed tube is supported in a bearing member 56 provided with suitable ball bearings 57.

The coal is prevented from packing in the bottom of the hopper 18 by means of an agitating loop 58 which is universally hinged therein at its one extremity in an eye bolt 59 and is mounted on a crank 60 at its other extremity. The crank 60 extends through the side wall of the hopper and carries a slotted lever 61 which extends downwardly opposite the extremity of the screw shaft 18.

A crank disc 62 is mounted on the screw shaft at this point and provided with a crank pin 63 which passes through and rides in the slot in the lever 61. It can be seen that as the shaft 18 rotates the crank pin 63 will oscillate the agitating loop 58 to prevent packing of the coal in the hopper.

It might be possible for gas to back up through the feed tube into the feed chamber 18. This gas is then withdrawn through a gas conduit 64 extending to the intake of the blower 26.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. In a stoker of the type having a feed screw; a ratchet wheel secured to said screw; a cam shaft adjacent said screw; a cam on said cam shaft; a lever lying across said cam; a ratchet

pawl at one extremity of said lever engaging said ratchet wheel so that as said cam rotates, it will reciprocate said pawl to rotate said ratchet wheel, an overload release device comprising: a pivot member supporting the other extremity of said lever; means for allowing said pivot member to move laterally when said feed screw encounters a predetermined resistance; means for guiding the lateral movement of said pivot member; and a stoker control-switch operated by the lateral movement of said pivot member.

2. In a stoker of the type having a feed screw; a ratchet wheel secured to said screw; a cam shaft adjacent said screw; a cam on said cam shaft; a lever lying across said cam; a ratchet pawl at one extremity of said lever engaging said ratchet wheel so that as said cam rotates, it will reciprocate said pawl to rotate said ratchet wheel, an overload release device comprising: a pivot shaft extending through the other extremity of said lever; stationary bearing members supporting said pivot shaft; and movable bearing members holding said pivot shaft down against said stationary members and a spring acting against said movable bearing members.

3. In a stoker of the type having a feed screw; a ratchet wheel secured to said screw; a cam shaft adjacent said screw; a cam on said cam shaft; a lever lying across said cam; a ratchet pawl at one extremity of said lever engaging said ratchet wheel so that as said cam rotates, it will reciprocate said pawl to rotate said ratchet wheel, an overload release device comprising: a pivot shaft extending through the other extremity of said lever; stationary bearing members supporting said pivot shaft; movable bearing members holding said pivot shaft down against said stationary members; a yoke extending between said movable bearing members; and a spring forcing said yoke and said movable bearing members downwardly against said pivot shaft.

4. In a stoker of the type having a feed screw; a ratchet wheel secured to said screw; a cam shaft adjacent said screw; a cam on said cam shaft; a lever lying across said cam; a ratchet pawl at one extremity of said lever engaging said ratchet wheel so that as said cam rotates, it will reciprocate said pawl to rotate said ratchet wheel, an overload release device comprising: a pivot shaft extending through the other extremity of said lever; stationary bearing members supporting said pivot shaft; movable bearing members holding said pivot shaft down against said stationary members; a yoke extending between said movable bearing members; a spring forcing said yoke and said movable bearing members downwardly against said pivot shaft; and a control switch actuated by the upward movement of said yoke.

5. The combination of a cam; a motor driving said cam; a lever extending across and resting against said cam; a ratchet drive device actuated by the movement of one extremity of said lever; a cross shaft pivotally supporting the other extremity of said lever; receiving means for supporting said cross shaft; and resilient means holding said cross shaft in said receiving means until the resistance of said ratchet drive reaches a pre-determined point.

6. The combination of a cam; a motor driving said cam; a lever extending across and resting against said cam; a ratchet drive device actuated by the movement of one extremity of said lever; a cross shaft pivotally supporting the other extremity of said lever; receiving means for supporting

5 said cross shaft; resilient means holding said cross shaft in said receiving means until the resistance of said ratchet drive reaches a pre-determined point; and an electric switch in circuit with said motor positioned to be actuated in consequence of the movement of said cross shaft from said receiving means.

7. The combination of a cam; a motor driving said cam; a lever extending across and resting 10 against said cam; a ratchet drive device actuated by the movement of one extremity of said lever; a cross shaft pivotally supporting the other extremity of said lever; a fixed half bearing for each 15 extremity of said cross shaft, said bearings being positioned on the cam side of said lever; a movable half bearing holding the cross shaft in each fixed half bearing; a yoke member extending between said movable half bearings; a spring forcing said yoke and said movable bearings against 20 said shaft to hold the latter in said fixed bearings until the load on said ratchet drive reaches a predetermined point; and an electric switch for controlling the operation of said motor in consequence of the movement of said yoke against said spring. 20
